UNITED STATES PATENT OFFICE.

VICTOR L. CUNNYNGHAM, OF PITTSBURG, PENNSYLVANIA.

STATION-INDICATOR.

SPECIFICATION forming part of Letters Patent No. 404,384, dated June 4, 1889.

Application filed January 14, 1888. Serial No. 260,678. (No model.)

To all whom it may concern:

Be it known that I, VICTOR L. CUNNYNGHAM, of Pittsburg, in the county of Allegheny and State of Pennsylvania, have invented a new and Improved Station-Indicator, of which the following is a specification, reference being had to the annexed drawing, forming a part thereof, in which a longitudinal section of my improved station-indicator is shown.

5 The object of my invention is to construct a simple and efficient station-indicator to be operated by electricity or mechanical devices, so that a series of indicators may be placed on the different cars of a train and operated 10 simultaneously by the conductor or engineer.

15 My object is further to provide a simplified form of apparatus for application to street-cars, stages, and other single vehicles.

20 My invention consists in a casing provided with a compartment for cards having printed on their faces the names of stations, the cards being arranged to be moved forward by an endless belt, an escapement for allowing the cards to drop into sight and afterward to 25 drop into a receptacle in which they are stored for use, and devices for operating the endless belt, escapement, and the storing mechanism, all as hereinafter more fully described.

30 The casing A' is divided into four compartments B² B' C' D', the compartment D' communicating with the compartment B' by means of the opening t. The partition which separates the compartment B' from C' is slot- 35 ted longitudinally to receive the endless belt F', which passes over rollers c² c³, journaled in the casing A'. The endless belt F' is pro- 40 vided with a series of apertures d for receiving a stud e, projecting from the bracket G' and the teeth of the roller c³, so that when 45 the roller c² is revolved by the means herein- after described the belt will be moved for- 50 ward the thickness of one card N'. The bracket G' is formed of the base-piece f, the upright g, and brace h. The cards N' are re- 55 tained in the compartment B' by springs 1, 2, attached to the upper and lower walls of the compartment, the springs being bent inwardly 60 toward each other, so as to engage the upper 65 and lower edges of the cards and prevent them 70 from being transferred to the lower compart- 75

ment D', except when forced forward by the movement of the belt F'. In the lower compartment D' is arranged a follower J', provided with the springs v² v³, which bear upon the bottom of the compartment and upon the partition between the said compartment and compartment C'. The cards N' in the lower compartment are engaged by the rods a², the forward ends of which are provided with inwardly-projecting catches d', and the cards dropped into the lower compartment D' are held against the thrusts of the rods a² by a block k². To the bottom of the casing A', in the rear part thereof, is pivoted a lever L', 60 which is pivotally connected with the rods a², and upon the end of the shaft of the roller c² is placed a ratchet-wheel k³, which is engaged by a pawl l', pivoted to the lever m', pivotally connected to the rod a². The pawl l' is kept 65 in engagement with the wheel k³ by the spring n', attached to the lever m' and bearing upon the end of the said pawl.

In the compartment B² of the casing A' is journaled a shaft E', provided with a pinion 75 o', and carrying a plate p', upon one side of which are printed the words "Next station is," and upon the other side the words "This station is." A rod M' is pivoted to the upper end of the lever L' and provided at its for- 80 ward end with a rack q', which engages the pinion o'. The lever L' is pressed forward by a spring O'.

In the rear wall of the casing A' is inserted a cylinder P', provided with a piston r', hav- 85 ing a piston-rod s' passing through the forward end of the cylinder and pivotally connected with the lever L'. A flexible pipe t' communicates with the forward end of the cylinder P', and in the rear wall of the cylinder P' is formed an aperture u' to permit of the escape of air as the piston is forced backward, in the manner presently to be described. The cylinder P' is used when it is desired to 90 operate the mechanism by means of compressed air or steam; but when it is desired to operate it by means of a cord or strap the cylinder P' may be dispensed with, and a cord or strap v³ is attached to the lever L', as indicated by dotted lines.

100 The operation is as follows: When the lever l is forced backward by the action of the steam

or air on the piston r' , or by pulling the cord v^3 , the cards N' in the compartment D' are drawn backward, the pawl l' is moved back, so as to engage another tooth of the ratchet-wheel k^3 , and the plate p' is turned so as to display the words "This station is," and the name of the station is displayed on the card below it in the compartment B' . Upon releasing the lever L' , either by allowing the air or steam to escape from the cylinder P' or by releasing the cord v^3 , the spring O' returns the lever L' to its normal position, and the lever in returning to its normal position draws back the cards N' in the compartment D' , and at the same time turns the lever m' , so as to cause the pawl l' to move forward the ratchet-wheel k^3 one notch, thereby turning the belt F' so as to move forward the cards N' in the compartment B' and discharge one card through the opening t into the compartment D' ; at the same time it returns the plate p' to its normal position, thus displaying the words the "Next station is," the name of the next station being shown upon the face of the first card in the series contained by the compartment B' .

Having thus described my invention, I claim as new and desire to secure by Letters Patent—

1. In a station-indicator, the combination, with a casing provided with a compartment for containing cards bearing the names of the streets or stations and having an aperture in one end of its bottom, of an endless carrier working in the bottom of the compartment for moving the cards over the aperture therein, and means for operating the endless carrier, substantially as described.

2. In a station-indicator, the combination, with a casing provided with compartments communicating with each other, of a series of cards bearing the names of the streets or stations and arranged in the upper compartment, an endless belt, a projection or bracket carried by the belt and engaging the cards, and means, substantially as described, for imparting motion to the endless belt, substantially as herein shown and described.

3. In a station-indicator, the combination, with a casing provided with compartments communicating with each other, of a series of cards bearing the names of the streets or stations and arranged in the upper compartment, an endless belt provided with a bracket engaging the cards, a ratchet-wheel on the shafts of one of the rollers of the endless belt, a spring-actuated pawl engaging the ratchet-wheel, a pivoted lever, a connection between said lever and pawl, and means for operating the lever, substantially as herein shown and described.

4. In a station-indicator, the combination of a casing provided with compartments communicating with each other, an endless belt working in the bottom of the upper compartment and provided with a bracket, a ratchet-wheel on the shaft of one of the rollers of the endless belt, a pawl engaging the ratchet-wheel, a pivoted lever, a connection between the said lever and pawl, and an air or steam cylinder having its piston-rod connected to the said lever, substantially as specified.

5. In a station-indicator, the combination, with a casing provided with a compartment for containing cards bearing the names of the streets or stations and having an aperture in one end of its bottom, a carrier for moving the cards over the aperture in the bottom of the said compartment, and means for operating the carrier, of a rotating plate arranged above the compartment and operated from the card-moving mechanism, substantially as herein shown and described.

6. In a station-indicator, the combination, with a casing provided with compartments communicating with each other, of an endless belt for transferring the cards carrying the names of the streets or stations from one compartment to the other, card-holding arms in the compartment into which the cards drop after being displayed, and means for operating the said belt and arms, substantially as herein shown and described.

7. In a station-indicator, the combination, with a casing divided into compartments communicating with each other, of an endless belt for transferring the cards carrying the names of the streets or stations from one compartment to the other, a ratchet-wheel on one of the rollers of the endless belt, a lever pivoted in the casing, card-holding arms connected to the lever, a second lever pivoted in the casing and to the first-named lever, a spring-pawl carried by the second lever and engaging the ratchet-wheel, and means for operating the first-named lever, substantially as herein shown and described.

8. In a station-indicator, the combination, with a casing divided into compartments communicating with each other and an endless belt for transferring the cards carrying the names of the streets or stations from one compartment to the other, of a lever pivoted in the casing, card-holding arms in the lower compartment and connected to said lever, a follower in the said lower compartment, a second lever pivoted in the casing and connected to the first-named lever, a spring-pressed pawl on the upper end of the second lever, a ratchet-wheel on one of the rollers of the endless belt, a shaft in the top compartment provided with a plate and a pinion, and a rack engaging the pinion and connected with the first-named lever, substantially as herein shown and described.
